UNITED STATES PATENT OFFICE.

THOMAS J. CARTER, OF INDIANAPOLIS, INDIANA, ASSIGNOR TO CARTER'S BESTEVER BAIT COMPANY, OF INDIANAPOLIS, INDIANA, A CORPORATION OF INDIANA.

DESIGN FOR AN ARTIFICIAL CASTING-BAIT.

57,311.

Specification for Design.

Patented Mar. 15, 1921.

Application filed February 21, 1920. Serial No. 360,395. Term of patent 14 years.

To all whom it may concern:

Be it known that I, THOMAS J. CARTER, a citizen of the United States, residing at Indianapolis, in the county of Marion and State of Indiana, have invented a new, original, and ornamental Design for Artificial Casting-Baits, of which the following is a specification, reference being had to the accompanying drawings, forming part thereof.

The drawing shows my new design. Figure 1 is a perspective view of an artificial

casting bait, showing my new design; and Fig. 2 is a front view thereof.

I claim as my invention:

The ornamental design for an artificial casting bait, as shown.

In witness whereof, I have hereunto set my hand at Indianapolis, Indiana, this nineteenth day of February, A. D. one thousand nine hundred and twenty.

THOMAS J. CARTER.
